UNITED STATES PATENT OFFICE

WILLIAM KELSO, OF PITTSBURGH, PENNSYLVANIA, ASSIGNOR TO THE MC CONWAY & TORLEY COMPANY, OF PITTSBURGH, PENNSYLVANIA, A CORPORATION OF PENNSYLVANIA

UNCOUPLING DEVICE

Application filed August 31, 1928. Serial No. 303,337.

My invention relates to an uncoupling device for actuating the locking mechanism of a car coupler so as to cause it to assume the positions required to unlock and open the coupler knuckle.

Car couplers which are in use at the present time are generally provided with means for restraining an accidental unlocking movement of the locking block which serves to prevent an outward rotation of the knuckle. The function of preventing accidental unlocking of the coupler as the result of shocks and jars incident to train movements is usually performed by the lock-lifter or other means for moving the knuckle locking member to unlocked position. While the means for restraining accidental unlocking of the coupler may be generally relied upon to perform the intended function, particularly where the speed of trains is moderate, it is the object of my invention to afford improved means for preventing the coupler lock from accidentally moving to unlocked position, the improved means being simple in form and reliable in operation and being capable of employment in conjunction with means now in use for locking the lock in locked position, thereby serving to supplement the latter and more fully insuring against accidental release of the coupler knuckle.

The principal feature of the invention consists in constituting an uncoupling device as a plurality of relatively movable lever members, one of which is adapted to actuate the other to cause the latter to perform an uncoupling movement resulting in an unlocking movement of the coupler lock, and in combining therewith a bracket rigidly mounted on the car, the said bracket having a pivot post or fulcrum extending through the lever members and being formed below the center of said pivot with a lug adapted to cooperate with one of said lever members to prevent the latter from accidentally performing an uncoupling movement.

Other features of the invention pertaining to advantageous structural details and relations of parts will hereinafter appear and be pointed out in the claims.

In the drawings illustrating a preferred embodiment of the invention:

Figure 1 is a plan view of an uncoupling device constructed in accordance with the invention, showing its relation to the end of a railway car, the parts being in locked position.

Figure 2 is an elevational view of the construction shown in Figure 1, the parts being in locked relation.

Figure 3 is a fragmentary view, partly in elevation and partly in vertical section, showing the relation of the lever members to the pivot or fulcrum bracket when the lever members are in normal locked relation.

Figure 4 is a fragmentary view, partly in elevation and partly in vertical section, showing the inner lever member released from interlocked relation with the pivot bracket as a result of the initial unlocking movement of the outer lever member.

Figures 5 and 6 are views corresponding with Figure 4 but illustrating respectively the positions assumed by the parts when the coupler lock is in lockset position and at the end of the knuckle opening movement of the uncoupling device.

Figure 7 is a detail side elevational view of the lever fulcrum or pivot bracket.

Figure 8 is a detail front elevational view of the fulcrum bracket.

The car coupler 1 illustrated in the drawings for the purpose of disclosing the relation of the improved uncoupling device thereto is of the well-known standard D-type wherein the locking block is moved to locked position by a lifter 2 which extends upwardly through an opening in the top wall of the coupler head for operative connection to the uncoupling device. When in locked position the lock-lifter 2 cooperates with the shoulder upon the interior of the coupler head to prevent the locking block by which outward rotation of the coupler knuckle is normally restrained from accidentally creeping upward to unlocked position.

The locking mechanism, forming a part of the car coupler assembly, is adapted to be unlocked by an uncoupling device involving an uncoupling lever consisting of an inner

member 3 and an outer member 4 whose adjacent ends overlap and are mounted upon the outwardly projecting pivot post or fulcrum 5 of a bracket 6 rigidly secured to the car body. The inner end portion 7 of the lever member 3, which extends through the usual eye at the upper end of the lock lifter 2 for a distance sufficient to accommodate the lateral movements of the coupler, is 10 preferably of cylindrical form. The outer arm 8 of the lever member 4 may be of any desired shape and preferably terminates adjacent the side of the car. By pressing downwardly upon the arm 8 of the outer lever member, which is accomplished either by hand or by foot, an uncoupling operation of the parts may be effected and if the lever arm 8 is fully depressed it induces the extended unlocking movement of the coupler locking block necessary to produce an outward rotation of the knuckle.

The outer lever member 4 is pivotally mounted or fulcrumed between its ends upon the pivot post 5, the inner arm 9 of said member being bent so as to extend under the inner lever member 3 at a point between the pivot 5 and the coupler, thus enabling an uncoupling movement of the inner lever member to be effected by a downward movement of the outer arm of the lever member 4.

The outer end of the inner lever member 3 is formed with a vertical slot 10 for receiving the fulcrum post or pivot 5, the side walls of the slot preferably being parallel 25 and disposed closely adjacent the pivot pin in order to efficiently guide the outer end of the member 3 during its movements. The lever member 4 has a circular opening for receiving the fulcrum post and, together with the inner lever member 3, is maintained in assembled relation to the post by means of a washer 11 and nut 12. At an appropriate distance from its outer end the pivot post 5 is preferably shouldered, as at 13, to prevent undue inward movement of the lever members upon the post.

Formed on the bracket 6 and extending downwardly below the center of the fulcrum or pivot post 5 is a lug or projection 14 whose lower end 15 is disposed so as normally to extend across the path of unlocking movement of the outer end of the inner lever member 3. For cooperating with lug or shoulder 15 to prevent accidental unlocking movement of the inner lever member 3 and the lock-lifter 2 operated thereby, the member 3 is fashioned at its outer end with a downwardly extending projection or lug 16, the inner side of which is notched or stepped to 55 form a shoulder 17 which is intermediate adjacent vertical faces 18 and 19 respectively of the locking lug 16. As shown in Figure 3, when the parts are in a position corresponding to normal locked relation of the coupler locking mechanism the face 19 upon the

downwardly extending locking projection 16 is in overlapping engagement with the outturned end 15 of the lug 14 with which the fulcrum bracket is provided, thus preventing the inner lever member 3 from performing an uncoupling rotation around the pivot post 5. It will also be noted that in case of breakage of the inner portion of the lever member 3 or its disconnection from the lock-lifter 2, the engagement of the lower vertical shoulder 18 of the inner lever member 3 with the adjacent face of the outturned lug 15, carried by the fulcrum bracket, serves (see Fig. 6) to prevent excessive movement of the member 4 which might result in injury to the trainman, especially if the uncoupling device is operated by his foot.

When the trainman presses down on the outer end of the outer uncoupling lever member 4 its inner arm 9 presses upwardly on the under side of the inner member 3, thus causing the outer end of the latter to move directly upward until the upper locking face or shoulder 19 of the member 3 ceases to overlap the cooperating locking face 15 of the pivot bracket, the parts then occupying the relation illustrated in Figure 4. A further downward movement of the outer end of the lever member 4 causes the locking mechanism of the coupler to move to unlocked position. If, after having been depressed sufficiently far to unlock the coupler the outer arm of the lever member 4 is relieved of downward pressure, the downwardly facing undercut shoulder 17 of the inner lever member will seat upon the upper face of the outturned lug 15 of the fulcrum casting 6, as shown in Figure 5 and the said inner lever member will remain in a position corresponding to lockset position of the coupler locking mechanism.

If, however, downward movement of the outer end of the uncoupling lever member 4 is continued sufficiently far to cause an extended unlocking movement of the coupler lock for throwing the knuckle open, the uncoupling levers will assume the position shown in Figure 6, the lower vertical face or shoulder 18 of the inner lever member 3 standing in overlapped relation to the lug 15 on the pivot casting and thus serving to limit the uncoupling rotation of the lever mechanism in the event the movement of the uncoupling device has not already been arrested by the coupler lock coming into engagement with the coupler head at the end of its unlocking movement. When, as a result of a subsequent coupling rotation of the coupler knuckle, the coupler locking mechanism returns to normal locked position the inner lever member 3 rotates so as to unseat its undercut shoulder from the supporting lug 15 of the fulcrum bracket, thus permitting the lever members of the uncoupling device to resume locked position.

I claim:

1. An uncoupling device for actuating the locking mechanism of a car coupler, said device involving an uncoupling lever comprising an outer lever member and an inner lever member, said lever members being relatively movable and having overlapping portions and the outer lever member being adapted to actuate the inner lever member to cause the latter to perform an uncoupling movement, a bracket having a fulcrum for cooperating with the overlapped portions of said lever members, and means for preventing the inner lever member from accidentally moving to uncoupling position until after the outer lever member executes a movement toward uncoupling position, said means involving a lug spaced downwardly from said fulcrum and normally overlapping a portion of the inner lever member to prevent the latter from executing an initial rotary movement with respect to said fulcrum.

2. An uncoupling device for actuating the locking mechanism of a car coupler, said device involving an uncoupling lever comprising an outer lever member and an inner lever member, said lever members being relatively movable and having overlapping portions and the outer lever member being adapted to actuate the inner lever member to cause the latter to perform an uncoupling movement, and a bracket having a fulcrum for cooperating with the overlapped portions of said lever members, said bracket being provided below said fulcrum and in spaced relation thereto with a lug for cooperating with a downwardly projecting portion of the inner lever member, and said inner lever member having a downwardly projecting portion providing a plurality of shoulders extending at an angle to each other, one of said shoulders being adapted to overlap said lug to prevent the inner lever member from executing an initial rotary movement with respect to said fulcrum and the other shoulder being adapted to seat upon said lug to support the outer end of said inner lever member when the coupler locking mechanism is in lockset position.

3. An uncoupling device for actuating the locking mechanism of a car coupler, said device involving an uncoupling lever comprising an outer lever member and an inner lever member, said lever members being relatively movable and having overlapping portions and the outer lever member being adapted to actuate the inner lever member to cause the latter to perform an uncoupling movement, a bracket having a pivot post extending through the overlapped portions of said lever members, said inner lever member having an elongated slot for receiving said post and being provided below said slot with a plurality of shoulders disposed in angular relation, and said bracket being provided

below said post with a lug for cooperating with said shoulders, one of said shoulders being adapted to overlap the lug to prevent the inner lever member from executing an initial rotary movement with respect to said post and the other shoulder being adapted to seat upon said lug to support the outer end of said inner lever member when the coupler locking mechanism is in lockset position.

4. An uncoupling device for actuating the locking mechanism of a car coupler, said device involving an uncoupling lever comprising an outer lever member and an inner lever member, said lever members being relatively movable and the outer lever member being adapted to actuate the inner lever member to cause the latter to perform an uncoupling movement, a bracket having a pivot post forming a fulcrum for the lever members, said inner lever member being formed with a slot for receiving the post and having below said slot a downwardly projection portion which is stepped to provide upper and lower shoulders and an intermediate shoulder disposed at an angle to said upper and lower shoulders, and said bracket being provided below the pivot post with a lug adapted to cooperate with said shoulders, said upper shoulder normally overlapping said lug to prevent the inner lever member from executing an initial rotary movement with respect to the pivot post, said intermediate shoulder being adapted to seat upon said lug to support the outer end of the inner lever member when the coupler locking mechanism is in lockset position, and said lower shoulder being adapted to overlap said lug to limit the extent of rotation of the inner lever member with respect to the pivot post.

In testimony whereof I affix my signature.

WILLIAM KELSO.
